UNITED STATES PATENT OFFICE.

CLIFFORD ROBERTS, OF REIGATE, ENGLAND, ASSIGNOR, BY MESNE ASSIGNMENTS, TO UNITED SHOE MACHINERY CORPORATION, OF PATERSON, NEW JERSEY, A CORPORATION OF NEW JERSEY.

HEEL ASSEMBLY.

Application filed June 14, 1924. Serial No. 719,946.

The present invention relates to heels for boots and shoes and more particularly to complete heel assemblies embodying a lower or tread lift of rubber or similar material which may readily be attached during the manufacture of the boot or shoe.

In attaching tread lifts of rubber or similar material during the manufacture of shoes it is customary to assemble and attach the intermediate or upper leather lifts and rand to the shoe by one nailing operation and subsequently secure the rubber tread lift to the heel base so formed by a separate nailing and cementing operation. In certain cases the rubber lift, together with the intermediate lifts of leather or equivalent material, are assembled and retained in position for attaching by nails, cement, pegs, or equivalent means, and the composite heel body including all of the lifts is thereafter attached to the shoe by a single nailing operation.

It is the object of the present invention to provide a form of heel assembly which will simplify and reduce the cost of heels provided with a rubber tread lift.

With this and other objects in view, one feature of the present invention contemplates the provision of a rubber tread lift having a core member provided with a projection extending upwardly from the attaching face an amount approximating the thickness of the combined intermediate lifts and rand interposed between the rubber lift and the heel base of the shoe. A properly shaped lift or lifts of leather or equivalent material may be assembled with the heel in a manner to engage with the projecting core and be retained thereby in proper relation to the heel. The tread member and intermediate lift or lifts may then be attached to the boot or shoe by a single nailing operation and without the use of cement or similar holding material. The provision of a heel member of this form cooperating with suitably shaped intermediate lifts facilitates handling of the heel assembly during the attaching operation, provides a tight edge, and dispenses with the necessity of double nailing of the heel assembly to the boot or shoe.

A further object of the invention is to provide a heel of rubber or similar material which may be standardized as to shape irrespective of variations in the curvature of the heel seat of different styles of shoes and at-

tached to various styles of shoes by merely interposing rand members shaped in accordance with the desired shape of heel seat.

With this object in view, a further feature of the invention contemplates the provision of a heel assembly consisting of a whole heel of rubber or similar material and a rand of leather or equivalent material interposed between the attaching face of the whole heel and the heel base of the boot or shoe, the rand preferably being retained in assembled relation with respect to the heel by a projection extending upwardly in a manner to engage with the rand.

In the accompanying drawings illustrating the preferred form of the invention Fig. 1 represents a rubber tread member having an upwardly extending core; Fig. 2 represents a lift designed to cooperate with the core; Fig. 3 is a transverse section of the tread member shown in Fig. 1; Fig. 4 is a longitudinal section of the tread member shown in Fig. 1; Fig. 5 is an elevation of the heel assembly attached to a boot or shoe; Fig. 6 is a transverse section of the assembly shown in Fig. 5 with leather lift; and Fig. 7 is a longitudinal section of the same assembly.

As indicated clearly in Figs. 1, 3 and 4 of the drawings, a lift of rubber or similar material is indicated at 10, this lift having a plywood core 12 bonded therein and firmly united to the rubber body, as clearly described in certain copending applications previously filed by applicant. The lift 10 may be slightly curved about the marginal portion, as indicated at 14, to form a relatively close joint with the adjoining lift through distortion of the body. Extending upwardly from the plywood core 12 is a projection 16 of plywood or similar material. This projection is preferably located centrally of the heel body and is somewhat smaller in area than the main body of the plywood core. The upward extension of the projection 16 approximates the thickness of the intermediate lift or lifts and rand employed in the complete heel assembly. In the illustrated embodiment of the invention, a single lift 20 is employed, this lift serving the combined functions of an intermediate lift and rand, as indicated clearly in Figs. 6 and 7. The lift has a generally heel shaped contour and is recessed to provide an opening fitting the projection 16. With this construction, the lift

20 may be readily assembled with the tread member 10 and held in place by engagement of the projection 16 with the inside of the recess. The assembled heel may then be attached to the boot or shoe by a single series of nails, as indicated generally at 22, without the necessity of employing cement or equivalent material. Such a heel not only facilitates the assembling and securing of the various lifts to the boot or shoe but in addition represents a saving of leather which is substantial. It will be evident to those skilled in the art from an inspection of Fig. 2 that the intermediate lift 20 which may be of leather consists of a generally horse shoe shaped strip having the general form of a rand. This strip is interposed between the marginal portions of the tread member and the boot or shoe and is of sufficient width to afford the desired nailing area. The material removed in forming the recessed opening may be utilized for the production of other and similar lifts by proper cutting of the sheet of material in a manner which will be evident to those skilled in the art. Figs. 5 to 7 inclusive of the drawings illustrate the improved form of heel assembly as actually attached to a boot or shoe, in this case, the heel end of the sole being indicated at 25 as forming a curved heel seat or base. The heel assembly consisting of the lift 20 of leather or other suitable material and the tread member 10 is attached to the heel seat of the shoe through a single series of nails 22, the slight distortion of the tread member in attaching the boot or shoe serving to maintain a close margin between the tread member and the intermediate lift 20 without the use of cement.

40 Although the illustrated embodiment of

the invention is shown in connection with what is ordinarily termed a half heel, the heel being completed through the use of one or more intermediate lifts and a rand, it will be evident to those skilled in the art that 45 the tread member 10 may consist of substantially a whole heel with merely a thin rand member 20 interposed between the margin of the heel and the heel seat of the shoe indicated at 25. In this case, the projection 50 16 may be relatively shallow and of sufficient depth primarily to engage and retain the rand in assembled relation during the attaching operation. Such an arrangement would permit the manufacture of standardized 55 whole heels either with a flat attaching face or an attaching face with a slight curvature, the variation in curvature of different heel seats being compensated through different shaped rand members.

60 While it is preferred to employ the specific construction and arrangement of parts shown and described, it will be understood that this construction and arrangement is not essential except so far as specified in the 65 claim and may be changed or modified without departing from the broader features of the invention.

What is claimed is:

60 A heel for boots or shoes comprising a heel body of rubber or similar material having a core bonded therein with an upwardly extending projection, and one or more intermediate lifts superimposed above the heel body and having an opening surrounding 75 and engaging the projection to maintain the two members in assembled relation.

In testimony whereof I have signed my name to this specification.

CLIFFORD ROBERTS.
